UNITED STATES PATENT OFFICE

ADOLPH LANGSNER, OF CHICAGO, ILLINOIS, ASSIGNEE TO EUGENE DIETZGEN COMPANY, OF CHICAGO, ILLINOIS, A CORPORATION OF DELAWARE

PROCESS OF FORMING LEVELING-ROD CLAMPS

Original application filed November 30, 1927, Serial No. 236,746. Patent No. 1,723,893, dated September 17, 1929. Divided and this application filed September 11, 1929. Serial No. 391,726.

My invention relates to clamps for leveling rods used by surveyors and others, especially to that type of rod composed of two sections whereby the rod may be extended in length, the clamp serving to hold the two rod sections in various positions of adjustment.

One of the objects of my invention is to provide a simple and economical type of clamp wherein the frame thereof is formed of sheet metal and preferably of a sheet metal stamping bent into a sleeve-like form and upon which is rigidly mounted a metal yoke carrying the clamping screw which holds the rod sections in adjusted position.

Another object of my present invention resides in the manner of constructing the sheet metal sleeve or frame from sheet metal and in the provision of the apertures therein through which the scale markings may be viewed and in the manner in which it is provided with openings for the reception at attaching screws and the clamping screw.

Still another object of my invention resides in forming the frame of the clamp of sheet metal and particularly in the manner in which the openings in the sheet metal stamping are formed, which openings include the sight opening for the scale readings, the screw openings and the clamping screw opening.

Yet another object of my invention resides in the manner of forming this sheet metal frame from a single stamping and bending it into substantially rectangular shape and in mounting thereon the yoke which carries the clamping screw.

These and other objects of my invention will be apparent from a perusal of the following specification when taken in connection with the accompanying drawings, wherein:

Fig. 1 is a perspective view of a portion of the two rod sections of an extensible leveling rod, showing my improved clamp in position.

Fig. 2 is a vertical section with one of the rod sections removed and showing the clamping frame attached to the other rod section.

Fig. 3 is a detached perspective view of the sheet metal frame itself.

Fig. 4 is a perspective view of the yoke or bridge member unconnected with the frame or sleeve.

Fig. 5 is a sectional view transversely through the leveling rod showing the sleeve enclosing and embracing the rod section 10.

Fig. 6 is a plan view of the sheet metal blank cut to form and just before the same is bent into a rectangular shape as shown in Fig. 3.

Referring now to the drawings in detail, the rod is formed in two sections 10 and 12 in the manner common to extension leveling rods, said sections being adapted adjustably to carry in practice a target, which is well known in the art and, therefore, is not shown in the drawing. The upper section 12 may be termed the movable section, the lower section 10 being designed to rest upon the ground or the support. Ordinarily the front of the stationary section 10 has scale markings. The present invention relates particularly to the construction of a clamp for adjustably holding the two rod sections in relative positions of adjustment as shown for instance in Figure 1 of the drawings. Broadly considered, this clamp includes a sleeve or frame attached to one of the rod sections and adapted to surround the other rod section which slides through it and the frame or sleeve carries a bracket or a yoke in which is mounted a clamping screw so that by turning the clamping screw in the yoke, the inner end of the screw will be projected toward that section of the rod which slides through the sleeve and will firmly grip and clamp the rod section in any position of adjustment relative to the other rod section.

The particular features of my invention, in respect to this clamp, reside in its simple and economical construction and particularly in the manner in which it is made from a sheet metal stamping into the form of a sleeve, and the manner in which the yoke is mounted on the sleeve so as to hold the clamping screw while permitting the screw to pass through an aperture in the sleeve to clamp the rod section.

as desired. Referring now more particularly to the clamp, the frame, which is shown in perspective in Figure 3 of the drawings, is formed of heavy sheet metal, or other desired material, from the blank form shown in Figure 6 of the drawings. For instance, in my particular method of forming this frame or sleeve, I stamp out of a piece of sheet metal the blank shown in Figure 6. 10 During this stamping operation the blank 14 is also stamped with a relatively large opening 16 for exhibiting the scale markings. It will be noted that this opening 16 is formed at one end of the blank. At the opposite 15 end of the blank I preferably provide the screw openings 24. The frame or sleeve 14 when in the form shown in Figure 3 may be screwed to the upper section 12 of the rod as shown in Figure 5. These screw openings 24 are preferably formed simultaneously with the formation of the opening 16. The opposite shorter edges of the blank are also stamped or notched as at 18, so that when the blank is formed into sleeve-like 25 shape these notches 18 will register to form the clamping screw opening. These notches are also preferably stamped or formed simultaneously with the formation of the other cuts on the blank. In addition, the 30 marginal portions of these shorter opposite sides of the blank are provided with screw or rivet openings 26 to receive the bridge member, so that in this manner, when the bridge or yoke 30 is assembled to the sleeve, 35 it will not only be mounted thereon, but the rivet or screw fastenings 26 will serve to hold the sleeve ends together.

After the blank is formed as shown in Figure 6, it is then bent at substantially 40 rectangular shape as shown in Figure 3.

The yoke or bracket 30, shown in perspective in Figure 4, has a main body portion formed with lateral off-sets which in turn are provided with feet 32 designed to bear upon 45 that side of the wall of the frame in which the clamping screw hole 18 is formed. These feet either have threaded holes 50 formed in them to register with the screw openings 26 or are provided with rivet openings so that 50 the yoke may be riveted to the frame at this point. In this manner the yoke is held in position upon the frame in a rigid manner. The yoke, at an intermediate point, is formed 55 with a threaded bore preferably in the form of a hollow boss 42 which, when the yoke is assembled, comes opposite the clamping screw opening 18 of the sleeve. A clamping screw 22, having an outer end threaded adjustably to engage the threads of the boss 42, is mounted 60 so that its inner nose extends through clamping screw opening 18 of the sleeve and this screw is provided with a turning means in the shape of a wheel 40 by which the screw may be rotated. It will be noted that the 65 yoke 30 bridges this wheel so that as a re-

sult of this construction, the wheel is protected from injury or from being struck by objects. Furthermore, the hollow boss 42 prevents dirt from having access to the threads of the screw and provides a housing in which 70 grease may be retained for lubricating the screw.

Between the nose of the screw and the side of the rod section 10 there is interposed a leaf 75 spring 44. This is for preventing the nose of the screw from indenting the wood of which the rod is formed, and it also increases the area available for clamping engagement on the rod section. The spring has extensions 46 at each end bent at right angles 80 to the body of the spring. These engage the upper and lower edges of the frame and prevent the spring from moving longitudinally relatively to the frame. By preference the extensions 46 are sprung a trifle so that they 85 will converge slightly and grip the upper and lower edges of the side wall of the frame. Thus the spring is held somewhat after the manner of a clip, with the result that the spring will retain itself upon the frame 90 even though the rod section is not present. As the spring is resilient it can, of course, be readily pulled off, and it can be positioned by merely pressing it in place, but this construction forms a simple and effective means for 95 keeping the spring in position in the frame and simplifies the act of assembly.

From the foregoing description it will be evident that in my clamp the form of the component elements is extremely simple and 100 the number of pieces is reduced to the minimum. It will also be evident that the process of manufacturing is greatly simplified, as the blank 14 can be struck out of a single piece of metal while the various openings are simultaneously formed therein so 105 that the only machine work required is that of threading the clamping screw and the chambered housing. It will also be evident that after my device has been assembled, 110 there is no danger of parts working loose or falling out when in use. From a practical standpoint, there are no parts to become loose and this is of great importance when it is borne in mind that this form of device is intended to be used in the field where repairs 115 are next to impossible.

The present application is a division of my co-pending application, Serial No. 236,746, filed November 30, 1927, Patent No. 1,728,893, September 17, 1929.

Having thus described my invention, what I claim as new and desire to secure by Letters Patent is:

1. The process of forming a clamping member for a leveling rod which comprises stamping out a substantially rectangular blank of sheet metal and forming the blank with a scale mark sight opening and screw openings and providing the opposite margin- 125

al edges of the blank with notches and bending the blank to form a rectangular hollow sleeve with the notches in registration so as to provide a screw opening.

5 2. The process of forming a clamp for a leveling rod which comprises stamping out a substantially rectangular blank of sheet metal and forming the blank with a scale mark sight opening and screw openings and providing the opposite marginal edges of the blank with correspondingly disposed notches and with fastener openings, bending the blank to rectangular hollow sleeve-like form so that the notches register and form a clamping screw opening and fastening a bridge element to said abutting notched portions of the blank whereby to hold said abutting portions in fixed relation and whereby to secure the bridge to the sleeve.

20 3. The process of forming a clamp for a leveling rod which consists in cutting out a substantially rectangular blank of sheet metal while simultaneously cutting out a relatively large opening within the body of the metal to provide an opening to exhibit the scale markings and providing the other portions of the body of sheet blank with screw openings to receive the fastening screws for attaching the finished blank to the leveling rod.

25 4. The process of forming a clamp for a leveling rod which consists in cutting out a substantially rectangular blank of sheet metal while simultaneously cutting out a relatively large opening within the body of the metal to provide an opening to exhibit the scale markings and providing the other portions of the body of sheet blank with screw openings to receive the fastening screws for attaching the finished blank to the leveling rod, bending the blank into rectangular formation whereby the relatively large opening will form a wall opposite that portion of the blank in which the attaching screw openings are formed.

30 45 5. The process of forming a clamping member for a leveling rod which comprises providing a substantially rectangular blank of sheet metal with a scale mark sight opening and screw openings and providing the opposite marginal edges of the blank with notches, bending the blank to form a rectangular hollow sleeve with the notches in registration so as to provide a screw opening.

50 55 6. The process of forming a clamp for a leveling rod which comprises stamping out a substantially rectangular blank of sheet metal and forming the blank with a scale mark sight opening and screw openings and providing the opposite marginal edges of the blank with correspondingly disposed notches and with fastener openings, bending the blank to rectangular hollow sleeve-like form so that the notches register and form a clamping screw opening and fastening a bridge

element to said abutting notched portions of the blank, whereby to hold said abutting portions in fixed relation and whereby to secure the bridge to the sleeve.

7. The process of forming a clamp for a leveling rod which consists in forming a rectangular blank of sheet metal with a relatively large scale mark sight opening at one end of the blank and with a plurality of screw openings at the correspondingly opposite end of the blank, and forming the opposite edges with marginal notches and with additional openings to receive fastening means, and bending the blank into rectangular formation, so that the notched edges will approach each other, and whereby the notches will register to form an opening for the reception of the clamping screw.

In witness whereof, I have hereunto subscribed my name.

ADOLPH LANGSNER.
